Attorney

UNITED STATES PATENT OFFICE.

AARON LEROY SMART, OF VICKERY, OHIO.

WRENCH.

1,277,268.

Specification of Letters Patent. Patented Aug. 27, 1918.

Application filed October 29, 1917. Serial No. 198,940.

To all whom it may concern:

Be it known that I, AARON LEROY SMART, a citizen of the United States, residing at Vickery, in the county of Sandusky and State of Ohio, have invented new and useful Improvements in Wrenches, of which the following is a specification.

The present invention relates to improvements in wrenches of the ratchet type, and the primary object of the invention is to provide a ratchet mechanism for such wrench including a dog designed to engage between the teeth of the turning member arranged upon the head of the wrench whereby when such dog is swung to either side of the wrench it is brought into such engagement as to be effectively held in operative position, but at the same time permitting of the said dog freely ratcheting over the teeth of the turning member.

With the above and other objects in view the improvement resides in the construction, combination and arrangement of parts set forth in the following specification and falling within the scope of the appended claims.

In the drawings:

Figure 1 is a plan view of a wrench constructed in accordance with the present invention,

Fig. 2 is a side elevation of the same,

Fig. 3 is a sectional view approximately on the line 3—3 of Fig. 2,

Fig. 4 is a sectional view approximately on the line 4—4 of Fig. 1,

Fig. 5 is a perspective view of the dog,

Fig. 6 is a similar view of the spring pressed bolt which co-engages with the dog, and

Fig. 7 is a perspective view of the turnable member or socket head.

Referring now to the drawings in detail the wrench is broadly indicated by the numeral 10, the same including a handle 11 which in plan gradually increases in width from one of its ends to its opposite end, and the widened end 12 is provided with a round aperture 13. The handle 11 from its widened end is bifurcated for a suitable distance, and the end wall 14 provided by the said bifurcation is provided with a central aperture 15 which communicates with a comparatively wide depression or pocket 16. The rounded apertures are designed to provide bearings for the rounded socket member 17, the said socket being centrally formed with a widened member 18 of a

thickness equaling the distance between the inner walls provided by the slot or bifurcation in the handle, and the said member 18 is peripherally provided with spaced teeth 19.

Pivotedly secured, as at 20, between the arms provided by the bifurcated portion of the wrench is a dog 21. This dog is designed to project through the slot or bifurcation and is of a length whereby the same may be swung to bring either of its active or toothed edges 22—22 to engage between the teeth 19 of the socket member 17 upon either side of the wrench, whereby to permit of the socket member turning in a desired direction and prevent the turning of the said socket member in an opposite direction. The body of the dog 20 is centrally widened, gradually decreasing in width to the engaging or toothed ends thereof, and the said body, to the rear of the pivot, is provided with a substantially V-shaped depression 23, and the inner wall of the said depression is centrally provided with an aperture 24. This aperture is designed to receive the offset end 25 of a bolt member 26, the opposite or free end of the said bolt passing through the aperture 15 and entering the pocket 16. The bolt at a suitable distance from its offset end 25 is provided with transverse lugs 27, and the bolt has arranged thereon a helical spring 28 which is designed to exert a pressure between the wall 14 and the lugs 27. When the dog 21 is swung to bring one of its active faces or tooth in engagement between the teeth of the socket member 17 the bolt 26 will be brought to contact with one of the side walls provided by the V-shaped depression 23, and therefore out of longitudinal alignment with the pivot 20 of the said dog. The bolt having one of its ends contacting with one of the side walls provided by the V-shaped depression 23 in the dog 21 and its opposite end frictionally contacting with the opposite walls provided by the aperture 15 will be held against further angular movement, and consequently hold the active end of the dog in proper position with respect to the toothed portion 19 of the socket member 17.

Having thus described the invention, what I claim is:

1. A wrench including a handle having a toothed socket member journaled thereon, a dog centrally pivoted to the handle, and designed to be swung to either side of the

handle to engage between the teeth of the socket member, said dog having a V-shaped depression opposite and to the rear of its pivot, and the inner wall provided by the 5 depression having an aperture, a spring pressed bolt having an offset end received in the aperture, the handle having a pocket provided with a restricted opening through which the free end of the bolt enters the 10 pocket, and the said bolt adapted to be brought in locking engagement with the opposite walls provided by the restricted opening, when the pocket is swung to bring the 15 side walls provided by the referred to V-shaped depression in the pocket.

2. In a ratchet wrench, the combination with a handle having a widened end provided with a round opening, said handle being bifurcated longitudinally from its said 20 widened end, a round socket member journaled in the round opening of the handle and having a central enlarged portion provided with spaced teeth received in the bifurcation of the handle, the inner wall of 25

the bifurcation having an aperture, the said handle having a pocket communicating with the aperture, a centrally pivoted dog in the bifurcated portion of the handle designed to be swung to either side of the handle to 30 engage with the teeth of the socket member, said dog to the rear of its pivot having a V-shaped depression and the inner wall of the depression having an aperture at the juncture of the angular walls of the depression, a bolt having an angular end received in the aperture and designed when the dog is swung to engaging position to contact with one of the side walls of the V-shaped depression, offset lugs upon the 40 bolt, the free end of the bolt passing through the aperture in the end wall of the bifurcation of the handle and entering the pocket, and a spring member upon the bolt exerting a pressure between the end wall 45 of the bifurcation and the lugs upon the bolt.

In testimony whereof I affix my signature.

AARON LEROY SMART.
